Primary Examiner — Brett Miller*Assistant Examiner* — Sara Michie Pottenger(74) *Attorney, Agent, or Firm* — Occhiuti & Rohlicek LLP(57) **CLAIM**

The ornamental design for a bollard fence, as shown and described.

DESCRIPTION

FIG. 1 is a perspective view of a bollard fence, showing our new design, where a section of chain link fencing is shown with broken lines and forms no part of the claimed design; FIG. 2 is a front view of the bollard fence of FIG. 1; FIG. 3 is a rear view of the bollard fence of FIG. 1; FIG. 4 is a top view of the bollard fence of FIG. 1, where the broken line boxes and corresponding labels indicate areas of detail replicated in FIGS. 5A and 5B and form no part of the claimed design;

FIG. 5A is a detailed top view of an end post of the bollard fence of FIG. 1;

FIG. 5B is a detailed top view of a middle post of the bollard fence of FIG. 1; and,

FIG. 6 is a left-side view of the bollard fence of FIG. 1, the right-side view is a mirror image of the left-side view.
